COLLAPSIBLE PICNIC TABLE

Verne A. Smith, 14858 Washburn, Detroit 38, Mich.
Filed July 13, 1962, Ser. No. 209,699
6 Claims. (Cl. 297—159)

The present invention relates to a collapsible picnic table, and more particularly to a table construction which is easily erected for summer use and which may be disassembled to form a compact, space-saving unit for winter storage.

Outdoor barbecues and picnics have become increasingly popular in recent years. The backyard, cottage or public picnicking area form pleasant locales for such outdoor events. A desirable table construction for picnicking is one that is sturdy and weather-resistant to withstand the elements, and yet is capable of being dismantled for storage or transportation. The standard picnic table is a permanent construction. Because of its large size it cannot conveniently be stored in the basement or garage during the winter. Additionally, it is not transportable from place to place in the family car. The present invention provides a picnic table which is of sturdy construction and appealing to the eye and is also readily disassembled for winter storage or for transportation in a vehicle.

It is an object of the invention to provide a collapsible picnic table construction.

Another object of the invention is to provide a table construction having a tripod-like leg structure which may be readily collapsed but which, when assembled with the other elements of the table, forms a stable support.

Another object of the invention is to provide a tripod-like leg construction which cooperates with a table top and bench structure to form a complete table, the tripod being openable to different positions to permit the table top and bench structure to be positioned at different horizontal levels to exactly accommodate the persons who are to use the table.

A further object of the invention is to provide a key or locking element for the tripod-like construction, the key being effective to secure the tripod in different open positions.

A still further object of the invention is to provide a bench structure having seating elements which are releasably secured together, the bench structure being capable of disassembly for storage or transportation purposes.

Other objects of this invention will appear in the following description and appended claims, reference being had to the accompanying drawings forming a part of this specification wherein like reference characters designate corresponding parts in the several views.

In the drawings:

FIGURE 1 is a perspective view of one embodiment of the collapsible picnic table of the present invention assembled and ready for use;

FIGURE 2 is an enlarged perspective view of the upper end of the tripod leg construction of the table of FIGURE 1 showing the structure for pivotally securing the legs together and the key for locking the tripod structure in open position;

FIGURE 3 is a sectional view of a portion of the table top showing one of the table legs extending through an opening therein;

FIGURE 4 is a top plan view of one corner of the bench structure illustrating the means for attaching the seating elements together; and

FIGURE 5 is a sectional view of a portion of the locking key showing means for holding the key relative to the table legs.

Before explaining the present invention in detail, it is

2

to be understood that the invention is not limited in its application to the details of construction and arrangement of parts illustrated in the accompanying drawings, since the invention is capable of other embodiments and of being practiced or carried out in various ways. Also, it is to be understood that the phraseology or terminology employed herein is for the purpose of description and not of limitation.

Referring to FIGURE 1, it will be seen that the table 10 comprises a tripod structure 12, a table top 14, a bench structure 16, and a locking member 18. These elements are preferably fabricated from wood. In describing the table construction, a three-legged tripod will be referred to. However, it should be appreciated that within the scope of the invention more than three legs may be utilized if desired.

The tripod 12 includes three legs 20, 22, 24 which are pivotally secured together at their upper ends to permit pivoting thereof with respect to each other. The leg-attaching structure is best seen in FIGURE 2. As will be noted, each leg has a split ring 26 attached to the upper end thereof. The ring 26 may be press-fitted or secured by screws to the leg. The ring 26 has a flange 28 with an opening 30 therein. A ring 32 extends through the opening 30 of each flange 28 to thereby secure the legs together. As will be appreciated, the legs may be pivoted on the ring 32 to assume the desired angular position with respect to each other.

The table top 14 is triangularly shaped and has an opening 34 in each corner thereof for the reception of one of the legs 20, 22, 24. As shown in FIGURE 3, the openings 34 have a larger diameter than the diameter of the legs to thus permit the legs to extend through the openings at an acute angle to the plane of the top 14. The upper edge 36 and lower edge 38 of the opening 34 bite into the angularly inclined leg 20. Downward or upward pressure on the table top is thus not effective to move the top upwardly or downwardly. The table top is thus retained in any desired horizontal position, such as the position illustrated in FIGURE 1.

The bench structure 16 comprises three seating elements 40, 42, 44. As shown in FIGURE 4, these elements are secured together at their ends by hinges 46 to form a triangular construction. The hinge 46 is similar to a conventional door hinge, having elements 48, 50 each of which is secured by screws 41, 43 to one of the seating elements 40, 42 at the end thereof. The elements 48, 50 have dovetailing ring elements 52, 54 to receive a pin 56. The pin 56 is removable when it is desired to disassemble the bench structure 16.

The bench structure 16 is positioned as shown in FIGURE 1 with the hinges 46 facing upwardly. In this manner the mitered ends of the seating element are pivoted into abutment and form a relatively rigid structure which is capable of supporting the weight of persons sitting thereon.

The tripod 12 is fixed in the desired open position by means of the locking member 18, as best illustrated in FIGURE 2. The locking member 18 has a triangular configuration similar to the table top 14, but is, of course, much smaller. Three openings 58 are provided in the corners of the member 18 for reception of the legs 20, 22, 24. The openings 58 are of larger diameter than the diameter of the legs so that the legs can be inclined at an acute angle to the plane of the member 18. The locking member 18 is received on the lower ends of the legs when the tripod is completely collapsed, and with the table top 14 and bench structure 16 being removed therefrom. The locking member 18 grips the legs 20, 22, 24 and will maintain the tripod 12 in any desired open position. The table top 14 and bench structure 16 also act to hold the tripod in the desired open position. However, it has been

found that the table construction is more stable when the locking member 18 is utilized.

As shown in FIGURE 5, the locking member 18 is held in place by means of a shoe 64 which frictionally engages the leg 20. The shoe 64 is positioned in the opening 58 and is driven into engagement with leg 20 by a thumbscrew 66 having a ball and socket connection 68 therewith. The thumbscrew 66 is threadingly received in an internally threaded sleeve 70 which is press fitted in an opening provided in the locking member 18.

In assembling the table, the locking member 18 is first received on the legs 20, 22, 24. The member 18 is moved up the legs a sufficient distance to open the tripod for the reception of the table top 14 which is then inserted on the legs. The member 18 and table top 14 are then moved upwardly on the tripod legs until the desired pyramid-shaped configuration of the tripod is achieved. The thumbscrew 66 is then tightened to lock the assembly in this position. As will be appreciated, the wider the tripod base, the higher the table top will be positioned. The table top is preferably positioned at a higher level if the table construction is to be utilized by adults and at a lower level if the table is to be utilized by children. After the locking member 18 and table top 14 have been positioned, the bench structure 16 is assembled in place around the tripod. This completes assembly of the table. The table may be disassembled in the same manner for storage or transportation.

Having thus described my invention, I claim:

1. A collapsible picnic table comprising at least three legs, means pivotally securing said legs together at one end thereof; a table top having spaced apart openings therethrough, one of said openings being provided for each of the legs, said table top being removably received on the legs intermediate the ends thereof with the legs extending through said openings to form a pyramid-shaped structure, and a removable bench structure surrounding and engaging the legs beneath the table top, said bench structure comprising a plurality of elongated seating elements joined together at their ends in a configuration concentric with the base of the pyramid-shaped structure.

2. A collapsible picnic table comprising at least three legs, means pivotally securing said legs together at one end thereof, a table top having spaced apart openings therethrough, one of said openings being provided for each of the legs, said table top being removably received on the legs intermediate the ends thereof with the legs extending through said openings to form a pyramid-shaped structure, a locking member of smaller area than the table top, said locking member having spaced apart openings therethrough, one of said locking member openings being provided for each of the legs, said locking member being removably received on the legs adjacent to the pivotally secured ends thereof with the legs extending through the locking member opening, said locking member acting to hold the legs in the aforementioned pyramid-shape, and a removable bench structure surrounding and engaging the legs beneath the table top, said bench structure comprising a plurality of elongated seating elements joined together at their ends in a configuration concentric with the base of the pyramid-shaped structure.

3. A collapsible picnic table comprising at least three legs, means pivotally securing said legs together at one end thereof, a table top having spaced apart openings therethrough of larger diameter than the diameter of the legs, one of said openings being provided for each of the legs, said table top being removably received on the legs intermediate the ends thereof with the legs extending through said openings at an acute angle to the plane of the table top to form a pyramid-shaped structure, and a removable bench structure surrounding and engaging the

legs beneath the table top, said bench structure comprising a plurality of elongated seating elements joined together at their ends in a configuration concentric with the base of the pyramid-shaped structure.

4. A collapsible picnic table comprising three or more legs, means pivotally securing said legs together at one end thereof, a table top having spaced apart openings therethrough of larger diameter than the diameter of the legs, one of said openings being provided for each of the legs, said table top being removably received on the legs intermediate the ends thereof with the legs extending through said openings at an acute angle to the plane of the table top to form a pyramid-shaped structure, a locking member of smaller area than the table top, said locking member having spaced apart openings therethrough of larger diameter than the diameter of the legs, one of said locking member openings being provided for each of the legs, said locking member being removably received on the legs adjacent to the pivotally secured ends thereof with the legs extending through the locking member openings at an acute angle to the plane of the locking member, said locking member acting to hold the legs in the aforementioned pyramid-shape, and a removable bench structure surrounding and engaging the legs beneath the table top, said bench structure comprising a plurality of elongated seating elements joined together at their ends in a configuration concentric with the base of the pyramid-shaped structure.

5. A device as claimed in claim 4 and further characterized in the provision of hinge means detachably securing the seating elements together at their ends, said hinge means comprising a hinge element on each end of each seating element, and a pin detachably securing adjacent hinge elements together.

6. A collapsible picnic table comprising three or more legs, means pivotally securing said legs together at one end thereof, a table top having spaced apart openings therethrough of larger diameter than the diameter of the legs, one of said openings being provided for each of the legs, said openings being provided adjacent the outer periphery of the table top and being spaced apart at equal intervals, said table top being removably received on the legs intermediate the ends thereof with the legs extending through said openings at an acute angle to the plane of the table top to form a pyramid-shaped structure, a locking member of smaller area than the table top, said locking member having spaced apart openings therethrough of larger diameter than the diameter of the legs, one of said locking member openings being provided for each of the legs, said locking member being removably received on the legs adjacent to the pivotally secured ends thereof with the legs extending through the locking member openings at an acute angle to the plane of the locking member, said locking member acting to hold the legs in the aforementioned pyramid-shape, and a removable bench structure surrounding and engaging the legs beneath the table top, said bench structure comprising a plurality of elongated seating elements joined together at their ends in a configuration concentric with the base of the pyramid-shaped structure.
